UNITED STATES PATENT OFFICE.

ROBERT BURNS, OF CHICAGO, ILLINOIS.

CAR JOURNAL-BOX.

SPECIFICATION forming part of Letters Patent No. 714,095, dated November 18, 1902.

Application filed March 5, 1901. Serial No. 49,924. (No model.)

To all whom it may concern:

Be it known that I, ROBERT BURNS, of Chicago, in the county of Cook and State of Illinois, have invented certain new and useful 5 Improvements in Car Journal-Boxes; and I do hereby declare that the following is a full, clear, and exact description thereof, reference being had to the accompanying drawings, and to the letters of reference marked thereon, 10 which form a part of this specification.

This invention relates to a novel journal box for car-axles constructed to prevent the abstraction by unauthorized persons from the box of the bearing-brass which receives the 15 wear of the axle.

The invention consists in the matters hereinafter set forth, and more particularly pointed out in the appended claims.

As journal-boxes for railway-cars are at 20 present constructed the bearing-brasses may be readily removed therefrom by raising the box with a suitable lifting device a distance sufficient to permit the brasses to be raised clear of the flanged ends of the journals. As 25 a result of this prevailing construction in journal-boxes in common use it is easily possible for large numbers of bearing-brasses to be annually stolen from cars, the work of abstracting the same from the boxes being 30 so small as to enable the same to be removed in a very short time and without exciting suspicion. As a result great loss is sustained by railroad companies, and the apprehension of the thieves requires a great deal of skill 35 and entails much expense and annoyance. Moreover, the loss of the bearing-brasses is often not discovered until the axle has been ruined by running in contact with the hard material of the box.

40 It is the purpose of my invention to provide means which may be embodied in new journal-boxes or which may be attached to boxes already in use which will prevent the journal-boxes being raised sufficiently to permit 45 removal of the bearing-brasses by unauthorized persons and which is so constructed as to enable an authorized person to readily remove the brasses and substitute others therefor.

In the drawings, Figure 1 is a longitudinal 50 vertical section of a journal-box containing my improvements. Fig. 2 is an enlarged sectional view of the parts immediately associ-

ated with my invention. Fig. 3 is a transverse section on line 3 3 of Fig. 2. Fig. 4 is a longitudinal vertical section of a box, showing a modification of my invention. Fig. 5 is a detail section of a part of Fig. 4 on an enlarged scale. Fig. 6 is a view of a wrench for manipulating the several movable parts.

Referring first to the construction shown in 60 Fig. 1, A designates the journal-box, provided with the usual hinged door or lid A'; B, the axle therein, and C the brass, on the concave lower surface of which is formed the bearing-surface for the axle and secured in 65 the box in any suitable manner.

The lower wall of the box is provided about midway between the ends thereof with a thickened portion D, having the form of a short vertical tube, the upper end of which projects above the lower wall of the box and the lower end of which depends a distance below the box. Within the bore of said tube is located a stop-stud E, which has screw-threaded connection with the tube and 75 which projects upwardly therefrom a distance into the box, said stud terminating below the axle B. The stud is slotted at its lower end, whereby it may be engaged by a suitable tool to move the stud toward and 80 away from the axle. The stud is locked in position within the tube by means of a short locking-stud F, which has screw-threaded engagement with the bore of the tube, permitting it to be moved toward and away from 85 the stud E. The locking-stud is provided with an angular head f, adapted to be engaged by a socketed tool to turn the same into and out of its locking position. The stop-stud is adjusted to its proper position before 90 the locking-stud is inserted into place, and thereafter the locking-stud is moved up against the stop-stud to hold it in place.

In order to prevent access by an unauthorized person to the bore of the tube to withdraw the locking and stop studs, the tube is provided with a closing-cap G, which fits over the lower end thereof and has screw-threaded connection therewith. Said cap is made exteriorly cylindric to prevent its being removed 100 by an ordinary wrench and is provided with a circumferential groove g, having an angular bottom adapted to receive a special form of wrench by which the cap is removed.

In practice a special tool or implement is provided for removing the several parts of the device described, consisting of a thin plate-wrench, which enters the groove *g* of 5 the nut, and a shank having on one part a socket to receive the lower end of the locking-stud and on another part a tapered end to enter the slotted end of the stop-stud.

When the parts are in the position shown in 10 Fig. 1, it will be seen that if an attempt be made to raise the box the stop-stud will come in contact with the axle before the box has been raised sufficiently to permit the brass to clear the axle, so as to enable the same to 15 be removed. Before the box can be removed, therefore, the stop-stud must be lowered, which cannot be accomplished without removing the cap and lowering the locking-stud. It will be observed, therefore, that a person 20 not provided with an implement such as before mentioned cannot quickly abstract the bearing-brass from the box, and in order that an unauthorized person may gain access to the box, therefore, a greater amount of time 25 is required than the conditions would warrant, so that the chances of the brasses being stolen are practically eliminated.

When a new brass is to be substituted by an authorized person, the cap and locking- 30 stud are removed and the stop-stud lowered the required distance. The box is then raised by a suitable lifting device, as a jack, until sufficient space is provided between the axle and the box to clear the brass. A new brass 35 is then substituted, the box lowered, and the parts of the safety device again adjusted to the positions shown in Fig. 1.

In Fig. 4 I have shown my improvements 40 constructed to be applied to a box already in use. In said construction the tube *H* is removably connected with the box, being inserted from the interior of the box through an opening in the lower wall thereof. Said tube is provided with a head or flange *h*, 45 which extends laterally beyond the opening into horizontal bearing engagement with the bottom wall of the box. The tube is provided on each side thereof below the flange *h* with lateral lugs *h'*, which fit within sockets in the 50 lower wall of the box, preventing said tube from rotating with respect to the box.

A lock-nut *H'* has screw-threaded engagement with the lower exposed end of said tube and bears against the lower surface of the 55 box and locks the tube from vertical movement. The other parts of the device are shown as made like the similar parts in Fig. 1 and before described, and said parts are designated by like reference-letters.

60 It is obvious that many changes may be made in the details of construction, in the size, and proportions without departing from the spirit of my invention, and I do not wish, therefore, to be limited to such details except as hereinafter made the subject of specific claims.

I claim as my invention—

1. The combination with a car journal-box, a removable bearing-brass and an axle journaled therein, said box being provided at its 70 end with an opening through which the brass is inserted into and removed from the box, of means for preventing unauthorized removal of said brass comprising a removable stop located opposite to the bearing-brass and 75 closely adjacent to but out of contact with the axle, the brass being made of such thickness relatively to the space below the axle and to the distance between the axle and stop, when the latter is in its uppermost position, 80 that said brass may be removed from or inserted into the box when the stop is retracted from the axle and without removal of the axle but cannot be removed from or inserted into the box when the stop occupies its normal 85 uppermost position.

2. The combination with a car journal-box constructed to permit the removal and replacement of its bearing-brass without removal of the journal, of a stop arranged opposite the 90 seat of the bearing-brass and normally removed from but closely adjacent to the periphery of a journal located in said box, said stop being movable nearer to or farther from the seat of the bearing-brass, substantially 95 as described.

3. The combination with a car journal-box having a removable bearing-brass, and a shaft or axle journaled therein, of means to prevent unauthorized removal of said brass consisting 100 of a movable stop located opposite the bearing-brass of the box and adjacent to but normally out of contact with the shaft or axle, substantially as described.

4. A car journal-box having means to prevent unauthorized removal of the bearing-brass, said means consisting of an adjustable stop arranged opposite the seat of the brass, and means for locking said stop in adjusted positions, substantially as described. 105

5. The combination with a journal-box and a brass removably seated therein, of a stop arranged opposite to the seat of the brass and movable toward and from said seat, said stop being designed to prevent the raising of the 115 box from an axle journaled therein sufficiently to permit the removal of the brass without disassembling of the parts of the box.

6. A journal-box provided in its lower wall with a non-rotative removable tubular part 120 which projects below said box, a vertically-movable stop-stud located in the tubular part and projecting into the box, a locking-stud engaging the stop-stud, and a closing-cap fitted to the lower end of the tubular part, substantially as described.

7. A journal-box provided in its lower wall with a non-rotative removable tubular part extending through the lower wall of the box and provided with radial lugs which engage 130 notches in the wall of the box, a locking-ring having screw-threaded engagement with the

tubular part and bearing against the wall of the box, a stop-stud movable vertically within said tubular part and projecting into the box, and means for closing the lower end of said part, substantially as described.

In testimony that I claim the foregoing as my invention I affix my signature, in presence

of two witnesses, this 27th day of February, A. D. 1901.

ROBERT BURNS.
